MERCHANDISE COVER CONTAINER

Filed Dec. 2, 1927

INVENTOR.
William Edward Snaman
BY Jas. P. Snyder
ATTORNEY.

UNITED STATES PATENT OFFICE

WILLIAM EDWARD SNAMAN, OF PITTSBURGH, PENNSYLVANIA

MERCHANTISE-COVER CONTAINER

Application filed December 2, 1927. Serial No. 237,251.

My invention relates to containers for covers which latter are used for covering divers kinds of marketable merchandise displayed on racks, stands, shelving and the like, to protect the goods against deterioration from dust, rain and soil at times other than during business hours. At the present time exposed merchandise on display, in the manner stated, is carefully covered at the close of the business day, with large sheets of cloth, which, when not in use, must be properly folded and stored, thereby involving considerable tedious labor and occupying valuable storage space.

Important objects of the present invention are to provide a container, for housing merchandise covers, of the character described, which forms a unitary part of the merchandise display device with which it is associated; which may be readily adapted and installed to any type of merchandise display structure already installed without material changes to the latter, as well as form a component part of a new display structure; which greatly facilitates the manipulation of the cover when covering and uncovering the merchandise; which does not occupy any space that is available for other purposes; which is simple in its construction and arrangement, durable and efficient in its use, attractive and ornamental in appearance, compact, and comparatively inexpensive to manufacture and install.

To the accomplishment of these and such other objects as may hereinafter appear, the invention resides in the novel construction, combination and arrangement of parts herein specifically described and illustrated in the accompanying drawings, but it is to be understood that changes, variations, and modifications of the invention may be resorted to which come within the scope of the claims hereunto appended.

In the drawing wherein like numerals of reference designate corresponding parts throughout the several views:—

Figure 1 is a side view of a circular garment display rack shown with a cover and my improved container therefor, with portion thereof shown in cross section.

Figure 2 is a top plan view of the cover container with the lid and merchandise cover removed therefrom.

Figure 3 is an end view of an elongated stationary type of garment display rack embodying a modified form of the present invention, and with parts shown in cross section.

Figure 4 is a top plan view of the modified form of the device with the lid and merchandise cover removed therefrom.

Referring in detail to the drawing Figure 1 illustrates a circular garment display rack of the ordinary construction now commonly in use. The circular display rack comprises the vertical standard 2 which has its lower end fixed to a wheeled base 3 to permit of the shifting of the entire rack when it is desired to change the location of the latter. An annular suspension ring 4 is revolvably connected to the standard 2, by means of the integrally formed arms 5 and the hub 6, as shown, or in any other suitable manner. The suspension ring 4 is disposed adjacent to the upper end of the standard 2, and provides a suspension element from which the garments 7, to be displayed, are suspended from removable garment hangers 8.

A cylindrical container 9, embodying the present invention is mounted on the top of the suspension ring 4, and is preferably secured to the latter to rotate therewith, but may be fixed to the standard 2 instead if desired. The container 9 may be constructed from any suitable material, preferably sheet metal, and is provided with a bottom 10 and an open top.

A circular lid 11 is provided for the open top of the container 9, and is supported on the upper portion of the standard 2, which projects centrally through and above the container 9. The lid 11 comprises a pair of associated semi-circular portions, which are joined together by a hinge 12. The semi-circular lid portions carry respective portions of a split hub clamp 13, which will function to engage the standard 2 and maintain the lid 11 at any position on the standard 2 when the lid portions are disposed in horizontal alignment relatively to each other.

However, when either or both of the lid portions are raised, the lid may be shifted vertically on the standard 2 to effect covering or uncovering of the container 9. When 5 the lid 11 is resting upon the top of the container 9 in the closing position, either of the pair of lid portions may be raised independently of the other to afford access to the container 9. If desired the lid 11 may be dispensed with entirely.

10 A resilient split or open annulus 14 is positioned on the bottom 10, of the container 9, and normally engages the inner periphery of the container 9. The annulus 14 is maintained in position in the container 9 by a series of inwardly disposed, overlapping retaining lugs 15 which are fixed in circumferential alignment on the inner side of the wall of the container 9. In positioning the 15 annulus 14 under the retaining lugs 15, or when effecting its release therefrom, it is only necessary to contract the said annulus 14, as the latter is resilient and split.

10 The annulus 14 is provided for maintaining the upper end of the enclosure member or garment cover 16 within the container 9. The garment cover 16 is constructed from relatively light, thin, textile fabric cloth and is intended to be draped over the garments 7, on the display rack, to completely cover same on all sides, with the exception of the bottom or lower side thereof, as clearly shown in Figure 1. The garment cover 16 is preferably constructed to provide several separate associated sections, the marginal side edges of which when the same are draped over the garments 7 overlap each other to efficiently exclude the entrance of any extraneous matter therethrough. The garment cover 16 may also be constructed to provide a unitary tubular structure, if desired, instead of comprising several separate sections as hereinbefore described.

15 The upper ends of the several garment cover sections are provided with hems 17 having open ends. The annulus 14 is extended into and through the hems 17 and detachably secured in position in the container 9, in the manner stated. As the circumference 20 of the annulus 14 is very much less than a circumference surrounding the suspended garments 7, it will, of course, be essential to closely gather the upper end of the garment cover 16 on the annulus 14 to provide the necessary fullness to the garment cover 16 to permit of the latter to envelope the entire 25 racked garment suspension.

30 The capacity of the container 9 is sufficient to receive and store the entire garment cover 16, without requiring that the latter be neatly folded and stacked therein. When it is desired to remove the garment cover 16 from the racked garments, it is only necessary to toss and pile the same into the container 9.

35 The principle of the modified form of the device, illustrated in Figures 3 and 4, is identical to that described, relatively to the preferred form, and shows the adaptation of the present invention to a stationary, elongated 40 type of garment display rack 18. The container 19 is mounted on and suitably fixed to the top of the latter, and extends throughout the entire length thereof. The container 19 is provided with a split cover 20, which is 45 hingedly secured thereto. The container 19 is further provided with a longitudinally extending partition wall 21, which divides the former into two equally sized and similarly arranged storage chambers. The upper ends 50 of the garment cover sections, indicated at 22 and 23, are detachably connected to a pair of rods 24, which are removable and disposed to extend along respective side walls of the container 19, adjacent to the bottom thereof. In 55 storing the garment cover sections 22 and 23, the same are placed in respective chambers of the divided container 19. Figure 3 illustrates the cover section 22 draped over the 60 garments on one side of the display rack 18, and the cover section 23 stored within its chamber of the container 19. As this chamber display rack is comparatively narrow, the front ends of the cover sections 22 and 23, and likewise the rear ends thereof, may 65 readily be drawn together and secured to overlap each other, whereby the racked garments 25 are completely enclosed and protected.

70 While the primary feature of the present invention resides in the provision of a racked merchandise display cover container, which is arranged to form a part of the display rack itself, to facilitate and expedite the covering and uncovering operations, it will here be 75 noted that my improved racked garment cover container may be constructed to embody appropriate ornamental features conforming with the construction of the merchandise display rack with which it is associated, and provide embellishment that will appreciably enhance the general appearance of the combined structure.

80 While illustrating and describing the device as embodied in certain types of garment display racks, it will be obvious that the present invention may be readily adapted to any other class of merchandise display structures, and that variations in the forms, proportions, and minor details of construction may be resorted to without departing from the spirit or sacrificing any of the advantages of the invention, as defined in the claims hereunto annexed.

85 What I claim is:

90 1. In a merchandise display device, the combination of a textile fabric cover member for enclosing said device, a container supported on the top of said device for storing 95

said cover member when not in use, a lid for said container, and removable means for detachably securing the upper end of said cover member to the inside of said container.

5 2. In a merchandise display device of the character described, the combination of a textile fabric cover member adapted for enclosing said display device, a cylindrical container supported on the top of the device for storing said cover member when not in use, a resilient open annulus detachably engaging the upper end of said cover member, and means for removably securing said annulus in said container.

10 15 3. In a merchandise display device, the combination of a textile fabric cover member for enclosing said device, a container supported on the top of said device for storing said cover when not in use, and removable means for detachably securing the upper end of said cover member on the inside of said container.

In testimony whereof I affix my signature.
WILLIAM EDWARD SNAMAN.
